UNITED STATES PATENT OFFICE.

LOUIS MATULA, OF CLEVELAND, OHIO.

LATHE GRINDING ATTACHMENT.

1,229,496.

Specification of Letters Patent. Patented June 12, 1917.

Application filed August 8, 1916. Serial No. 113,741.

To all whom it may concern:

Be it known that I, LOUIS MATULA, a subject of the King of Hungary, and a resident of Cleveland, in the county of Cuyahoga and State of Ohio, have invented new and useful Improvements in Lathe Grinding Attachments, of which the following is a specification.

This invention relates to improvements in apparatus for grinding and truing small articles in a lathe and particularly in grinding the centers used with the lathe.

One of the objects of the invention is to provide an apparatus which may be easily and quickly applied in its operative position upon the "ways" or "shears" of a lathe, the device being entirely self-contained, and adapted to be driven by frictional contact with the larger step of the cone pulley used in driving the lathe.

A further object is to provide such an apparatus by means of which an abrading wheel may be driven and manipulated, the frictional driving contact being attained through an adjustable lever system by which it may be controlled.

These and other objects, such as simplicity, durability of parts, and ease of operation, are attained by the novel construction and combination of parts hereafter described and shown in the accompanying drawings, forming a material part of this specification, and in which:

Figure 1 is a side elevational view of a conventional type of lathe or turning machine showing the general application of the invention.

Fig. 2 is an enlarged fragmental front view of the same.

Fig. 3 is a transverse sectional view, partially diagrammatic, of the same.

Fig. 4 is a longitudinal sectional view, showing an abrading wheel, its supporting and driving means.

Fig. 5 is a front view of the friction driving disk and its supporting arm.

Fig. 6 is a fragmental side elevational view showing the grinding attachment engaged with the compound rest of a lathe.

Fig. 7 is a side view of the holder in which the grinding attachment is secured, and

Fig. 8 is a fragmental side elevation view, showing the abrading wheel engaged with the holder.

The frequent use of some apparatus for truing lathe centers is a recognized necessity

as they rapidly wear from a true conical shape and when such wear occurs, work can no longer be accurately produced when held by the centers if they rotate eccentrically or if misshaped from a recognized standard.

The apparatus shown consists of a block 10, having a V shaped longitudinal recess 11 formed therein, and suited to the similarly shaped "ways" or "shears" of the lathe 65 bed at its front.

The block is shiftable longitudinally on the ways into such a position as may be desired and then held by the clamp plate 12, through the bolt 13, and adjusting screw 14 70 in an obvious manner.

Rigidly attached to the block 10 is a segmental plate 16, secured to the end thereof, and having a plurality of serrations 17 disposed upon its upper, arcuate edge and centered on the plate is a lever 18 held by the pivot 19 and provided with a manually operated handle 20 at its extreme upper end.

Attached to the lever 18 is a pawl 22 having an operating link 23 actuatable by a handle 24, normally held outward by means of the spring 25 from the operating handle 20.

Upon the opposite side of the lever 18 is a bracket element 28 which may be secured by screws 29, to the height required, the bracket 85 having an extending lug 30, in which, carried by the pivot 31, is a swinging bracket 32, the same being used as a mounting for the revoluble shaft 33, having at one end a friction disk 35, as of rubber, leather or fiber, adapted to impinge upon the peripheral driving surface of the cone pulley and held normally thereagainst by the spring 36, the tension of which is adjusted by movement of the lever 18, or which may be retracted when desired by movement of the lever.

The opposite end of the shaft 33 has secured to it a suitable length of flexible shaft 40, the same being engaged at its outer end 100 to a spindle 41, revolvably mounted in a bearing 42, the same being knurled or corrugated upon its exterior 43 so as to be conveniently held in an operator's hand. Provisions are made for receiving the sleeve 105 44 within the handle element, the sleeve being prevented from retracting by means of the spring-pressed pin 45, entering an annular groove 46 formed in the sleeve 44 as can best be seen in Fig. 4.

The front end of the handle has an enlarged head 48, of such diameter as to pre-

vent the hand from slipping and coming in contact with the wheel, and is bored to receive an annular ball bearing 50, held in position by the ring 51 in an obvious manner, thus permitting the shaft to readily revolve and taking the thrust of the wheel 52, secured between flanges 53 and 54 by the nut 55, on the screw threaded end 56 of the spindle 41.

10 As the compound rest may be set at any angle with the shears it is obvious that the abrading wheel 52 may be caused to travel in any angular direction, or moved in a plane parallel to the shear by the carriage 15 thus providing means for cylindrical grinding.

In operation, the block being secured upon the front "ways" and "shears" of the lathe in a proper location, the lever 18 is advanced to press the disk 35 against the periphery of the cone pulley to such an extent as to cause the shaft 40 to rotate, the handle 43 being manipulated in an obvious manner, so as to bring the wheel 52 into 25 contact with the lathe center or with whatever article it is desired to grind.

If the abrading wheel be in the compound rest it is possible to raise or lower same, by the action of the tool post and to move the 30 wheel toward the head or foot of the lathe by the carriage action.

Thus hardened lathe centers or other similar articles too hard to be turned by ordinary cutting tools, may be quickly and easily ground while in the lathe and without the necessity of employing a separate and 35 expensive machine for the purpose.

Copies of this patent may be obtained for five cents each, by addressing the "Commissioner of Patents, Washington, D. C."

Having thus described my invention, what I claim as new and desire to secure by Letters Patent is:—

1. In a grinder of the class described, the combination with an annular rotary element and a fixed support, of a block adjustably slidable on said fixed support, means for clamping said block to said support, a 40 segmental bracket carried by said block having teeth upon its arcuate upper edge, a lever pivoted to said bracket, a pawl, and means for operation thereof, combined with said lever, a bracket adjustable longitudinally on said lever, a friction disk pivotally carried by said bracket, means for pressing said disk against said rotary element, a flexible shaft driven by said friction disk, an abrading wheel operatively connected 45 with said flexible shaft and means for manually controlling said abrading wheel.

2. In a grinder, the combination with an annular rotatable element and a fixed support, of a block movable on said support, 60 means for clamping said block thereto, an arcuate bracket carried by said block, a manually operated lever pivoted on said block, a friction disk engageable with said rotary member, means for normally pressing said disk tensionally against said rotatable element, an abrading wheel, a mounting therefor, said mounting being adapted for manual operation, and connections between said abrading wheel through said operating means to said disk.

In testimony whereof I have signed my name to this specification.

LOUIS MATULA.
